METHOD AND APPARATUS FOR THE PREPARATION OF FLANGED CONDUIT

BACKGROUND OF THE INVENTION

Often times it is desireable to form an integral flange on a conduit wherein the resultant flange is generally radially outwardly extending. Various methods and apparatus are available to accomplish such flanging or forming of a malleable conduit such as steel pipe and the like. Forging and rolling techniques are satisfactory for the production of large quantities of flanged conduit of a single dimension and configuration. Often it is desireable to produce small number of flanged or shaped conduit ends of differing shapes and forms.

It is an object of this invention to provide an improved method and apparatus for flanging malleable conduit.

It is an object of this invention to provide a versatile, easily operated apparatus for the flanging of malleable conduit.

It is another object of this invention to provide a method of flanging malleable conduit on conventional metal working equipment such as an engine lathe.

DESCRIPTION OF THE INVENTION

The apparatus of the invention is in cooperative combination, a work holding means rotatably mounted on a support means, means to rotate the work holding means. The work holding means defining a bore passing there through and extending from a first end generally to a second end of the work holding means. The bore being generally coaxially disposed with the axis of rotation of the work holding means. The work holding means having attached there to a pattern. The pattern having a pattern surface disposed adjacent the first end and remote from the second end, the pattern defining a pattern bore generally coaxial with the axis of rotation of the work holding means. The pattern surface having the configuration of the back face of a desired flange. A forming roll retaining means positioned within the work holding means. The forming roll retaining means having first and second portions, the second portion having a forming roll rotatably supported thereon. A pivot means joining first and second forming roll means portions permitting axial misalignment of the first and second portions, means to selectively tension the forming roll support means toward the second end and means to axially displace the second portion of the forming roll support out of axial alignment with the first portion thereof.

The method of the present invention is a method of flanging a hollow generally cylindrical conduit. The steps of the method comprising rotatably supporting a hollow cylindrical conduit about a resiliently tensioned pivot, the pivot resiliently tensioned and moveable in an axial direction, rotating the conduit and applying a generally radial force to one inner edge thereof by means of a forming roll supported on a lever pivotally attached to said pivot and displacing said lever away from the axis of generation and rotation of said conduit until a flange of desired configuration is obtained.

DESCRIPTION OF THE DRAWING:

FIG. 1 is a schematic partly-in-section representation of an apparatus in accordance with the invention.

FIG. 2 is a schematic, the apparatus having therein a flanged conduit.

FIG. 3 is an enlarged partly-in-section view of a portion of the apparatus of FIGS. 1 and 2.

FIG. 4 is a schematic partly-in-section view of an alternate embodiment of the invention.

In FIG. 1 there is schematically depicted partly-in-section view of an apparatus in accordance with the invention generally designated by the reference number 10, the apparatus 10 comprises in cooperative combination a base or support bed 12 such as a lathe bed. A rotating means or head 14 such as a lathe head is affixed the bed 12. A hollow spindle 16 is rotably supported and rotated by the head 14. The spindle 16 has a first end 18 and a second end 20 and defines therein a passage way or bore 22 extending from the first end 18 to second end 20.

A work holding means or chuck 24 is affixed to the first end 18 of the spindle 16. The chuck 24 holds a pattern piece or master 26 having a face 28 remote from the second end 20 the face 28 having the desired configuration of a flange to be prepared and a work piece 29 to be flanged. A forming roll support means 30 extends into and through the bore 22. The support means 30 comprises a first portion 32 positioned generally within the bore 22 and a second portion 34 external thereto. The portions 32 and 34 are pivotally affixed to each other by pivot means 35. A generally frustoconical forming roll 36 is rotatably mounted on the second portion 34 generally concentrically or coaxially with the portion 32. The smaller end of the roll 36 is generally adjacent the face 28. The first portion 32 terminates generally adjacent second end 20 of the spindle 18. A selective tensioning means 36' such as a hydraulic cylinder and/or compression spring 37 is disposed in generally fixed relationship to the head 14 and is in operative engagement, such as by means of the piston rod of a hydraulic cylinder, with the first portion 32 of the support means 30 thereby permitting selective positioning within the bore in an axial direction, of the support 30 relative to the head 14. The maximum force exerted by the means 36' such as a hydraulic cylinder on the support 30 can be controlled by varying the pressure of the hydraulic fluid or oil. A displacing means 39 such as a lathe carriage is moveably mounted on the bed 12 generally adjacent the second end 34 of the support means 30. The displacing means 39 has a shoe or guide 38 beneficially having the form of a grooved roll or sheave which engages the second portion 34 of the roll support 30 and displaces it axially about the pivot 35 as depicted in FIG. 1, movement of the means or carriage 39 toward the head 14 through a camming action of the curved second portion 34 and the shoe 38 causes the end of the second portion 34 remote from the pivot 35 to move to a location wherein the axis of roll 36 is displaced generally normal to the axis of the spindle 16.

In FIG. 2 there is shown a view of the apparatus 10 of FIG. 1 wherein the displacing means 39 has moved forward to workholder 34 forming a flange 29a on workpiece 29. Note that pivot 35 has moved in the direction of the displacing means or carriage 39 and the tension means or cylinder 36' has moved toward the rotating means 14. Beneficially the face 28 is of either planar or convex configuration to produce a flange having a corresponding configuration. The apparatus of the invention as shown in FIGS. 1 and 2 is particu-

larly advantageous when preparing flanged components which require relatively little force such as 3 inch nominal pipe diameter Schedule 40 pipe in a 20 inch lathe (20 inch diameter swing).

In FIG. 3 there is shown an enlarged schematic cut away view of an apparatus 10a showing details of the pivot 35a forming roll 36a work piece 29b prior to formation of the flange such as the 29a. The work piece 29b is within a master 26a which in turn is held in chuck jaws 24a.

FIG. 4 schematically depicts an alternate embodiment of the invention generally designated by the reference numeral 40. The apparatus 40 is similar with the apparatus 10 of FIGS. 1, 2 and 3 with the exception that the chuck jaws 24a carry the master or pattern 26b which holds the work piece 29c and plurality of forming rolls 36b and 36c are employed. The roll 36b and 36c are rotatably supported on support members 34b and 34c respectively. The support members 34b and 34c are pivotably attached to member 32a by pivots 35b and 35c respectively. In the foregoing description of FIGS. 3 and 4 the alphabetical suffix to the reference numerals indicates parts of equivalent mechanical function thus chucks 24, 24a and 24b are equivalent in function. The embodiment of FIG. 4 is especially useful when relatively large parts are being flanged by simultaneously forcing member 34b and 34c apart (by a carriage and/or the independent means) workpiece 29c is flanged with only minimal radial thrust being placed on the bearings supporting the chuck 24b. In both varieties of the invention as shown and described the pivot points such as the pivot points 35, 35a, 35b, 35c move into and through the plane of the formed flange, as the support members 34, 34a, 34b or 34c are moved outwardly to form the flange using the apparatus and method such as has been herein before described, a wide variety of flanges are easily prepared.

I claim:

1. In cooperative combination, a work holding means rotatably mounted on, a support means, means to rotate the work holding means, the work holding means defining, a bore passing therethrough and extending from a first and generally to a second end of the work holding means, the bore being generally coaxially disposed with the axis of rotation of the work holding means, the work holding means having attached thereto, a pattern, the pattern having, a pattern surface disposed adjacent the first end and remote from the second end the pattern defining, a pattern bore gener-

ally coaxial with the axis of rotation of the work holding means, the pattern surface having the configuration of the back face of a desired flange, a forming roll retaining means positioned within the work holding means, 5 the forming roll retaining means having first and second portions, the second portion having a forming roll rotatably supported thereon, a pivot means joining first and second forming roll means portions permitting axial misalignment of the first and second portions, 10 means to selectively tension the forming roll support means toward the second end, means to axially displace the second portion of the forming roll support out of axial alignment with the first portions.

2. The apparatus of claim 1 wherein a plurality of 15 forming rolls are employed.

3. The apparatus of claim 1 wherein the work holding means and pattern are integral.

4. The apparatus of claim 1 wherein the means to selectively tension is a compression spring.

5. The apparatus of claim 1 wherein the means to selectively tension is a hydraulic cylinder.

6. The apparatus of claim 1 wherein the means to selectively tension is a compression spring and a hydraulic cylinder.

25 7. The method of claim 1 wherein the means to axially displace is a lathe carriage.

8. A method of flanging a hollow generally cylindrical conduit, the steps of the method comprising rotatably supporting a hollow cylindrical conduit about a 30 resiliently tensioned pivot means located within said conduit, said pivot means resiliently tensioned and moveable in an axial direction, rotating the conduit and applying a generally radial force to one inner edge thereof by means of a forming roll supported on a lever 35 pivotally attached to said pivot, and displacing said lever away from the axis of generation and rotation of said conduit until a flange of desired configuration is obtained.

9. The method of claim 8 wherein the lever is displaced sufficiently to form a flange on the conduit extending generally radially outwardly.

10. The method of claim 8 wherein the pivot is moved axially in a direction generally toward the lever as the lever is axially displaced.

45 11. The method of claim 8 wherein two forming rolls and two levers are employed and each lever is displaced generally away from each other generally in the place of the axis of rotation.
